UNITED STATES PATENT OFFICE

2,628,131

OIL BURNER

Herbert J. Haberstroh, Bristol, Conn.

Application April 14, 1950, Serial No. 155,969

1 Claim. (Cl. 299—133)

1

This invention relates to oil burners, and more particularly to an automatically adjustable, pressure responsive oil burner nozzle.

A main object of the invention is to provide an automatically adjustable oil burner nozzle which is simple in construction, dependable in operation, and which eliminates the necessity of changing nozzles or portions thereof to meet changes in the demand of the steam boiler or other boiler with which the burner nozzle is employed.

A further object of the invention is to provide an improved, automatically adjustable oil burner nozzle which is inexpensive to manufacture, involves relatively few parts, is rugged in construction, and provides a wide range of orifice adjustment responding automatically to changes in the pressure of the oil supplied to the nozzle.

Further objects and advantages of the invention will become apparent from the following description and claim, and from the accompanying drawings, wherein:

Figure 1 is a side elevational view, partly in longitudinal, cross-section, of an improved, automatically adjustable oil burner nozzle constructed in accordance with the present invention;

Figure 2 is an enlarged, cross-sectional view taken on line 2—2 of Figure 1;

Figure 3 is a cross-sectional view taken on line 3—3 of Figure 1;

Figure 4 is an enlarged, cross-sectional view taken on line 4—4 of Figure 1;

Figure 5 is an enlarged, cross-sectional view taken on line 5—5 of Figure 1;

Figure 6 is an enlarged, cross-sectional view taken on line 6—6 of Figure 1.

Referring to the drawings, 11 designates an elongated, tubular barrel formed at its forward end with a reduced, threaded portion 12. Threaded on portion 12 is a sleeve member 13 formed at its forward end with a reduced, threaded portion 14. Threaded on portion 14 is the apertured discharge cap 15. Cap 15 is formed at its central portion with the tapered orifice 16 which has a flared inner portion 17. Sleeve member 13 is formed with a conical recess 18 communicating with the end of the sleeve by passages 19, 19. Tangential whirl ports 20 are formed in the inner wall surface of the discharge cap 15, providing passages between the tapered portion 17 and the passages 19.

Threaded into the rear end of the barrel 11 is an oil supply fitting 21 formed with an oil inlet conduit 22 and having secured in its main

cavity a cylindrical strainer 23. The strainer 23 has apertured end walls 24, 25 which are sealingly secured to the internal wall surfaces of the main body portion of the fitting 21. The strainer end walls 24 and 25 are formed with apertures, such as shown at 26 in Figure 4. Threadedly secured on the rear end of the fitting 21 is a shouldered, hollow cylindrical member 27 having a forward wall element 28 formed with apertures 29, 29 communicating with the space rearwardly adjacent the apertured end wall 25 of the strainer 23. Sealingly secured to the wall 28 inside member 27 is an expansible resilient bellows member 30 having an inherent bias in a direction toward said wall. Designated at 31 is a rod member which extends axially through the barrel 11, the strainer member 23 and wall element 28, and is secured at its rear end to the rear wall of the bellows 30. The rear end portion of the rod 31 preferably is threadedly engaged in the rear wall of the bellows and is locked in adjusted position by a lock nut 32. Encircling the rod member 31 inside the bellows 30 is a coil spring 33 which bears between the wall 28 and the rear wall of the bellows, biasing the rod member 31 rearwardly. The forward portion of the rod member 31 extends slidably through the reduced forward portion 14 of the sleeve 13, the forward end of the rod 31 being tapered and engaging within the aperture 16 in the discharge tip 15, as shown in Figure 1. The rod member 31 extends slidably through wall 28 and slidably and sealingly through the end walls 24 and 25 of the strainer 23. The rear end of the rod member 31 is provided with a slotted head 34 which may be engaged by the blade of a screw driver or other similar tool for adjusting the position of the rod member. The member 28 is provided with a removable rear cap 35 whereby access to the slotted end 34 of the rod member 31 is available whenever required.

In operation, oil enters the inlet conduit 22 and then passes through the strainer 23 and the apertured forward end wall 24 thereof, passing through the barrel 11, the recess 18, the passages 19, the grooves 20, and past the end of the rod member 31 through the aperture 16, discharging from the tip 15 in an atomized condition. The rate of discharge is governed by the position of the tapered forward tip of the rod member 31. Oil also passes rearwardly through the apertured wall 25 of the strainer 23 and through the openings 29, 29 into the bellows 30, extending the bellows 30 rearwardly in accordance with the

pressure of the oil. The normal position of the rear wall of the bellows 30 is established by spring 33, which also establishes the normal clearance between the forward end of rod member 31 and the discharge opening in the tip 15. Rearward extension of the bellows 30 under the pressure of oil admitted into the bellows moves the rod member 31 rearwardly, enlarging the discharge passage between the forward end of the rod member and the discharge opening in the tip 15, whereby when the oil pressure is high, a relatively high rate of discharge of the atomized oil is obtained. When the pressure of the oil admitted into the inlet conduit 22 is small, the bellows 30 is in a relatively contracted condition, whereby the discharge passage at the tip 15 is relatively small and therefore the discharge rate of the atomized oil is similarly small. It will be therefore apparent that the discharge rate of the atomized oil at the burner tip is governed substantially in accordance with the value of the pressure of the oil furnished at the intake conduit 22. Automatic regulation of the discharge rate of the atomized oil is therefore obtained in accordance with the pressure of the oil furnished to the burner device. This enables the burner device to be employed over a wide range of different inlet oil pressures and automatically varies the rate of discharge of the atomized oil without the necessity of changing the sprayer tip whenever changes in demand of the steam boiler or other device employing the burner occur. The device functions to provide proper atomization of the oil over a wide range of demand conditions and prevents waste of oil, and also prevents inefficient combustion thereof. The device is especially applicable for use on marine vessels, such as warships and the like, wherein a considerable amount of rapid maneuvering is required. The use of the present device eliminates waste of time previously consumed in changing burners and enables a steady steam pressure to be obtained at all times, since the burners respond automatically to provide proper atomization and feeding of the fuel under all conditions of fuel supply pressure.

While a specific embodiment of an improved automatically self adjusting oil burner device has been disclosed in the foregoing description, it will be understood that various modifications within the spirit of the invention may occur to those

skilled in the art. Therefore, it is intended that no limitations be placed on the invention except as defined by the scope of the appended claim.

What is claimed is:

- 5 A fuel burner of the character described comprising a tubular barrel provided at its forward end with an apertured discharge tip, a valve rod axially and slidably supported within said barrel, said barrel being formed with a space around said rod, a perforated strainer engaged in said space and slidably receiving said rod, a shouldered, hollow cylindrical member having a forward wall element in closing engagement with the rear end of the barrel, said wall element slidably receiving said rod and having an aperture therethrough, means removably closing the open end of the hollow cylindrical member, an expandable bellows secured to said forward wall element rearwardly thereof and communicating with said aperture, 10 the rear portion of said valve rod being secured to the end wall of the bellows said bellows having an inherent bias in a direction to close the valve, spring means biasing the valve rod rearwardly to establish a normal amount of fuel discharge clearance at the burner tip, and a fuel inlet conduit connected to said space, whereby fuel may pass through said strainer both forwardly and rearwardly in the barrel, said bellows being expandable to retract said rod responsive to 15 increase in pressure of the fuel, whereby the fuel discharge opening at the burner tip is enlarged, 20 25 30
